UNITED STATES PATENT OFFICE.

FRANK GRYCKOWSKI, OF BEAVERTON, OREGON, ASSIGNOR OF ONE-HALF TO FRANK M. MAZUREK, OF BEAVERTON, OREGON.

MECHANICAL TOY.

Application filed January 10, 1924, Serial No. 685,896.

To all whom it may concern:

Be it known that I, FRANK GRYCKOWSKI, a citizen of the United States of America, residing at Beaverton, in the county of Washington and State of Oregon, have invented certain new and useful Improvements in Mechanical Toys, of which the following is a specification.

This invention relates to new and useful improvements in mechanical toys of the propelled type.

An important object of the invention is to provide a mechanical toy having a body portion properly formed to simulate any preferred type of animal and preferably of such a size that it will support the weight of a person's body.

A further object of the invention is to provide a mechanical toy of the above mentioned type which is provided with means for manually propelling the same and for controlling the direction of travel.

Other objects and advantages of the invention will be apparent during the course 25 of the following description.

In the accompanying drawings forming a part of this specification and in which like numerals are employed to designate like parts throughout the same,

Figure 1 is a central-vertical sectional view of the mechanical toy embodying this invention.

Figure 2 is a horizontal, transverse sectional view taken upon lines II—II of Fig. 1.

Figure 3 is a horizontal sectional view taken upon line III—III of Fig. 1.

Figure 4 is a vertical sectional view taken upon lines IV—IV of Fig. 1.

Figure 5 is a vertical sectional view taken 40 upon lines V—V of Fig. 1.

Figure 6 is a vertical sectional view taken upon line VI—VI of Fig. 1, and

Figure 7 is a longitudinal sectional view 45 of the head portion of the figure taken upon line VII—VII of Figure 1.

In the drawings, wherein for the purpose of illustration is shown the preferred embodiment of the invention, the numeral 5 designates the central, longitudinally extending portion of a base which further comprises the relatively long transversely extending rear portion 6 and the relatively short transversely extending front portion 7. In Fig. 5, the transversely extending rear portion 6 is illustrated as having depending

legs 8 at its outer ends which are provided for having journaled thereto the rear axle 9 which is provided with the ground engaging wheels 10 which are keyed to the said axle. The transversely extending front portion 7 is suitably, centrally apertured for receiving the pivot pin 11 which pivotally connects the front axle 12 to the said front portion 7. This front axle 12 is preferably in the form of a flat rectangularly-shaped bar which is provided with longitudinally, axially extending stub shafts 13 formed at its outer ends and upon which the front ground engaging wheels 14 are loosely mounted.

Suitably mounted upon this base is a formation which is intended to simulate an animal, which in this instance is a horse, which is formed of any suitable material and is preferably hollow. The trunk or body portion 15 of the animal is supported in suitable spaced relation to the base by means of the front legs 16 which are mounted upon the front transversely extending portion 7 and the rear legs 17 which are suitably mounted upon the rear transversely extending portion 6. The animal formation further includes the neck portion 18 and the head portion 19.

Extending vertically through the body or trunk portion 15 at points slightly rearwardly of the neck portion and front legs, there are provided spaced shaft hangers 20 which are adapted for supporting the transversely extending drive shaft 21 which is journaled in the said hangers 20. There is further provided a brace member 22 which extends between the upper and lower walls of the body or trunk portion and is employed for aiding in supporting the transversely extending drive shaft 21.

Suitably keyed to this drive shaft 21 is a large bevel gear 23 which is driven by the pair of pedals 24 that are carried by the levers 25 pivotally connected to the cranks 26 which in turn are suitably keyed to the outer projecting ends of the drive shaft 21. It will be seen by inspecting Figs. 1, 2 and 6 that the levers 25 extend downwardly through slots 27 formed in the opposite sides of the body portion 15.

Extending transversely of the body portion 15 and spaced rearwardly of the drive shaft 21, there are provided a pair of spaced brace bars 28 which have centrally journaled therein the longitudinally extending driven

shaft 29 having a bevel pinion 30 keyed to its front end and positioned in mesh with the bevel gear 23. Extending transversely of the body portion 15 and positioned rearwardly of the rear brace bar 28, there is provided a transversely extending shaft 31 having a bevel gear 32 keyed thereto which is constantly in mesh with a bevel pinion 33 keyed to the rear end of the longitudinally extending driven shaft 29. Suitably keyed to the transversely extending shaft 31 and positioned in proximity to the outer ends of the same are bevel gears 34 which are constantly in mesh with bevel pinions 35 keyed to the upper ends of the perpendicular shafts 36 which extend longitudinally of the rear legs 17. The lower ends of these perpendicular extending shafts 36 depend from the transversely extending rear portion 6 and are provided with bevel gears 37 which are keyed thereto. These bevel gears 37 are constantly in mesh with bevel pinions 38 keyed to the rear axle 9.

It will be seen that this arrangement of elements constitutes means for driving the rear ground engaging wheels 10 and that a person seated upon the body or trunk portion of the animal may move the latter forwardly or rearwardly over the ground by actuating the bevel gear 23 by means of the pedals 24 and their connections therewith. For the comfort and convenience of a person propelling the toy over the ground, a seat portion or saddle 39 is resiliently supported, by means of the springs 40, upon the body or trunk portion 15. Suitably secured to the seat portion or saddle 39 are side flaps or skirts 41 which depend and slidably engage the opposite sides of the body or trunk portions 15 and are employed for substantially concealing the spring 40.

Mounted in the central longitudinally extending portion 5 of the base is a perpendicular shaft 42 which extends above and below the said base portion 5. Suitably keyed to the depending portion of this shaft 42 is a sprocket wheel 43 having mounted thereon the length of sprocket chain 44 which is connected at its opposite ends to short lengths of cable or rope 45 and 46 which in turn are connected to the right and left hand ends of the front axle 12. The upper or perpendicularly projecting portion of the shaft 42 is suitably keyed to a second sprocket wheel 47 which operatively engages the section of sprocket chain 48. The opposite ends of this sprocket chain 48 are connected to the cables or ropes 49 and 50 which extend upwardly through the right and left hand front legs 16 respectively. The grooved rollers 51 are suitably secured to the lower ends of these front legs 16 and permit the said ropes or cables 49 and 50 to travel in angular paths. Extending transversely of the body or trunk portion 15 of the figure and positioned in

vertical alignment with the front legs 16 are spaced supporting bars 52 which have journaled therebetween the large grooved pulley 53. The upper ends of the ropes or cables 49 and 50 are connected to this grooved pulley 53 as shown in Figs. 1, 2 and 4. It will be seen by inspecting these figures that when the front axle 12 extends truly transversely or in parallelism with the front portion 7 of the base the means 54 which is employed for securing the upper ends of the ropes or cables 49 and 50 to the grooved pulley 53 is directly vertically in alignment with the vertical axis of the body portion or trunk of the figure.

Extending transversely of the neck portion 18 of the figure is a rotatable shaft 55 having keyed thereto the grooved rollers 56 which are positioned in proximity to the opposite ends of the said shaft 55. The head portion 19 is also provided with a transversely extending shaft 57 having keyed thereto the grooved rollers 58. The muzzle portion 19a of the head portion 19 is provided with a shaft 59 upon which are keyed the grooved rollers 60. In Fig. 7 there are illustrated spaced grooved rollers 61 which are positioned outwardly of the shaft and grooved rollers 59 and 60 respectively. These grooved rollers 56, 58, 60 and 61 are employed for forming two sets of guides for the opposite sides of a rope or cable 62 which is connected intermediate its length, as at 63, to the grooved pulley 53 at a point diametrically opposite the means 54 which connects the ropes or cables 49 and 50 to the said grooved pulley 53. The outer free ends of this rope or cable 62 are connected to the opposite ends of a strap 64 which is to be employed as a steering rein.

It will be seen that this arrangement of elements permits the person seated upon the saddle 39 to move the front axle 12 for permitting changing of the direction of travel of the figure. When the right hand side of the rein 64 is pulled upon, the rope or cable 62 will cause the grooved pulley 63 to travel in a counter-clockwise direction, when viewed from the front of the figure and this clockwise movement will exert a pull upon the rope or cable 50 which extends downwardly through the left hand front leg 16. This pull upon the rope or cable 50 will cause the shaft 42 to rotate in a clockwise direction, when viewed from above and this clockwise rotation of the shaft 42 will make the right hand end of the axle 12 be moved rearwardly while the left hand end will be moved forwardly.

It is now believed that the construction and operation of the various elements will be understood by one skilled in the art. It is very apparent that a person seated upon the saddle 39 may propel the figure over the ground by working the pedals 24 with his

feet and that the figure may be steered by pulling upon either side of the rein 64.

It is to be understood that the form of this invention herewith shown and described is to be taken as a preferred example of the same, and that various changes in the shape, size, and arrangement of parts may be resorted to without departing from the spirit of the invention or the scope of the sub-
joined claims.

Having thus described the invention, I claim:—

1. In a mechanical toy of the class described, a base, an animal figure mounted on the base, rear ground engaging wheels connected to the base, a front axle pivotally connected to the base, ground engaging wheels mounted on said axle, a shaft journaled in the base perpendicular to the front axle, a pair of sprocket wheels mounted on the shaft, a sprocket chain riding on one of the sprocket wheels and having its ends connected to the ends of the front axle, a second sprocket chain riding on the second sprocket wheel, a set of reins having its ends leading into the head of the animal figure, and means extending through the body of the

figure and connecting the ends of the reins to the ends of the second sprocket chain for pivoting the front axle to steer the toy. 30

2. In a mechanical toy of the class described, a base, an animal figure mounted on the base, a rear axle journaled on the base, ground engaging wheels keyed to the rear axle, front ground engaging wheels connected to the base, a bevel pinion keyed to the rear axle, a perpendicular shaft passing through the body of the animal figure, a bevel gear on the lower end of the shaft meshing with the bevel pinion on the rear 40 axle, a horizontally extending shaft journaled within the body of the figure, a gear connection between the horizontal shaft and the perpendicular shaft, a drive shaft journaled in the body of the figure and extending parallel to the said horizontally extending shaft, means for connecting the drive and horizontally extending shafts to cause the same to rotate in opposite directions, and manually operable means connected to 45 the drive shaft for driving the same to propel the toy.

In testimony whereof I affix my signature.
FRANK GRYCKOWSKI.
